SPEED GOVERNING MECHANISM

Hall Steen-Johnsen, Greensburg, Pa., assignor to
 Elliott Company, Jeannette, Pa., a corporation
 of Pennsylvania

Application June 30, 1950, Serial No. 171,399

2 Claims. (Cl. 264—7)

1

This invention relates to speed governing mechanisms for prime movers operated by fluid pressure, such as steam turbines.

It is among the objects of this invention to provide such a governing mechanism which is very sensitive to speed changes of the prime mover, and in which fluid pressure operated means control the operation of the fluid admission valves of the prime mover.

In accordance with this invention a fluid pressure operated servo-motor controls the admission valve or valves of a prime mover, such as a steam turbine. Admission of fluid under pressure to the servo-motor is controlled by a pilot valve that is operated by a second fluid pressure operated servo-motor. Admission of fluid under pressure to the second servo-motor is controlled by a governor pilot valve that is operated by a rotating centrifugal device which is responsive to the speed of the prime mover.

The centrifugal device, or governor, includes a support which is rotated continuously by the prime mover and which carries flyweights that are supported by rubber bushings rigidly connected with the support and flyweights. Swinging of the flyweights, due to centrifugal force, puts the bushings in elastic torsion. There is no friction for the flyweights to overcome. A floating rotary member, coaxial with the support, is rotated and moved axially by means of flexible strip means connecting it with the flyweights.

The governor pilot valve includes a valve member rigidly connected at one end to the rotary member of the governor coaxially thereof. A piston is secured to the valve member, and a housing rotatably and slidably receives the valve member and piston. The housing has a fluid passage therethrough that is controlled by the valve member and that is provided with an inlet end for fluid under pressure and a discharge end. The latter end is connected to the second servo-motor by a conduit, so that when the valve passage between the inlet and discharge ends is opened by the governor, fluid under pressure is delivered to the second servo-motor to actuate it. The valve housing also has a duct leading from the discharge end of its fluid passage to the adjacent side of the piston on the valve member, whereby to deliver fluid pressure to the piston in order to move the valve member axially to passage-closing position against the resistance of the governor.

The preferred embodiment of the invention is illustrated in the accompanying drawings, in which Fig. 1 is a view, partly in elevation and partly in vertical section, of my governing mech-

2

anism with its movable parts in an intermediate position; Fig. 2 is an enlarged plan view of the governor itself, partly broken away in section on the line II—II of Fig. 1; and Fig. 3 is an enlarged vertical section through the governor pilot valve when the turbine is not running.

Referring to Fig. 1 of the drawings, the governing mechanism is illustrated as used for controlling the steam admission valves of a steam turbine, although it will be understood that the mechanism is equally applicable to other forms of prime movers using other forms of fluid pressure. Only one of the several steam admission valves, with which the turbine may be provided, is shown. This valve 1 is in a steam line that is controlled by a main shut-off valve (not shown) which is closed to shut down the turbine. When the main shut-off valve is closed, the admission valve opens wide so that the full pressure of the steam will be delivered to the turbine as soon as the shut-off valve is opened again. The movable valve member 2 of the admission valve is moved up and down by an arm 3 on a rocker shaft 4. The outer end of the arm is pivotally connected to the upper end of a rod 6, the lower end of which is pivotally connected to a block 7. Screwed into the block is the upper end of a piston rod 8 that extends down through an open chamber 9 and into the cylinder 10 of a servo-motor 11 for the steam admission valve. The lower end of the rod carries a piston 12. In cases where it is desired to close the steam admission valves when the turbine is shut down and there is no fluid pressure for that purpose, a coil spring 13 may be compressed between the top of chamber 9 and a collar 14 mounted on the rod for urging the piston downward.

One side of the servo-motor cylinder block has an integral projection which forms a pilot valve 16 for the motor. For this purpose the cylinder block is provided with a downwardly extending bore in which a sleeve 17 is mounted. This sleeve is provided with axially spaced discharge ports 18 and 19 communicating with passages 20 and 21, respectively, extending from them through the block to the upper and lower ends of cylinder 10. Between these ports the sleeve is provided with another port 22 communicating with an inlet passage 23 through the block. Below the lower port 19 the sleeve is provided with an exhaust port 24 that connects with a passage 25 leading out of the block. Another exhaust port 26 is formed in the sleeve above port 18, and communicates with a passage 27 also leading out of the block. The flow of high pressure oil delivered to inlet pas-

sage 23 is controlled by means of a valve member 30 slidably mounted in sleeve 17. The major portion of this member is considerably smaller than the inside of the sleeve so as to provide an annular space between them, but the valve member has enlarged portions 31 and 32 which fit snugly in the sleeve so that when the valve member is in centered position, both discharge ports 18 and 19 will be closed. It will be seen that if the valve member is raised, the inlet passage 23 will be placed in communication with the upper discharge port 18, and the lower discharge port 19 will be connected with exhaust port 24. The passages that are opened when the valve member is lowered from centered position will be obvious.

The valve member 30 is raised and lowered in sleeve 17 by means of a stem 35 pivotally connected to its upper end and to a lever 36. One end of the lever straddles block 7, to which it is connected by a pivot pin 37, while the other end of the lever is pivotally connected to the lower end of a link 38 whose upper end is pivotally connected to one end of an arm 39. The central portion of this arm is pivotally mounted in a bracket 41 supported by a case 42. The other end of the arm is pivotally connected to the upper end of a piston rod 43 that extends down into a cylinder 44 formed in the case. The lower end of the rod carries a piston 46 which is urged upward in the cylinder by means of a coil spring 47. The piston and cylinder and spring form a governor servo-motor 48.

It will be seen that whenever piston 46 is moved downward, it will rock arm 39 clockwise and raise the right-hand end of lever 36. The lever, being fulcrumed on the pin 37, will raise the valve member 30 of pilot valve 16 so that oil entering the valve through inlet 23 will be delivered to the upper end of servo-motor cylinder 10. This will move piston 12 down in the cylinder and thereby pull the left-hand end of the lever down. The lever, then fulcruming on the lower end of link 38, will lower the valve member in the pilot valve to again close both discharge ports 18 and 19 of the valve. This will trap the oil in both ends of the servo-motor cylinder 10 and hold the piston therein stationary until the pilot valve is opened again. When the servo-motor piston is moved downward, the steam admission valve member 2 is moved toward closed position. Of course, upward movement of piston 46 in the governor servo-motor 48 will just reverse all the movement just described, and the steam admission valve will be opened.

In order to supply fluid pressure to the upper end of the governor servo-motor cylinder 44, a pipe 51 connects it with a governor pilot valve 52. This valve includes an open-ended housing 53, the inside of which is formed from a sleeve 54. The internal diameter of the sleeve is enlarged at its upper end to form a cylinder 56. A short distance below the enlarged portion the sleeve is provided with a radial inlet port 57 communicating with an inlet 58 through the housing adapted to be connected to a high pressure oil supply. At a little lower level the sleeve is provided with radial discharge ports 59 communicating with a housing discharge port 61 connected to pipe 51. At a still lower level the sleeve has an exhaust port 62. The sleeve also has a vertical passage or duct 63 connecting its discharge port 61 with the bottom of cylinder 56.

Rotatably and slidably mounted in sleeve 54 is a valve member 65 which has secured to its upper end a piston 66 disposed in the cylinder. The valve member extends out of the lower end

of the sleeve and is rigidly connected to a vertically movable rotary member 67 forming part of a centrifugal device, the rotation of which is controlled by the speed of the turbine as will be described presently. The valve member 65 has axially spaced cylindrical portions 68, 69 and 70 that fit snugly within sleeve 54, the upper and lower portions sealing the upper and lower ends of the smaller part of the sleeve. Between these cylindrical portions the diameter of the valve member is much smaller in order to form fluid passages. When the valve member is in exactly centered position, its middle portion 69 extends across the inner end of the sleeve's discharge ports 59 to close them. However, if the valve member is moved up or down only a few thousandths of an inch, the discharge ports will be placed in communication with either the inlet port 57 or the exhaust port 62, depending upon which direction the valve member is moved. Thus, when the valve member is moved down, high pressure oil passes through the pilot valve and pipe 51 to the upper end of the governor servo-motor 48. When the valve member is raised above centered position, spring 47 forces oil out of the upper end of the servo-motor cylinder 44 and back through the pilot valve discharge ports 61 and 59 and out of its exhaust port 62. When the valve member is in centered or closed position, any oil in the upper end of cylinder 44 is trapped therein to hold piston 46 stationary.

It also is a feature of this invention that while oil pressure is being delivered through pilot valve 52 to the governor servo-motor, the oil also will exert pressure against the lower surface of the valve piston 66 until the pressure is great enough to raise the piston far enough to close the valve by moving the valve member 65 up to centered position. Therefore, the high pressure oil passage through the pilot valve never opens more than a few thousandths of an inch before it is closed again by means of piston 66.

The speed responsive centrifugal device or governor which controls governor pilot valve 52 is described in detail in my copending patent application Serial Number 74,394, filed February 3, 1949, now Patent No. 2,546,911. It includes a flat head 75 which is rigidly mounted on the upper end of a shaft 76 that is rotated by a worm gear 77 driven by a worm 78 from the turbine shaft. Mounted on this head is a pair of laterally spaced parallel supporting members, which may be in the form of metal blocks 79. Between these blocks is a pair of flyweights 81 of any desirable form, the ones shown being more or less in the form of an inverted letter L. The upper portion of each weight is provided with a horizontal opening through which a pivot pin 82 extends. The parallel pins also extend through axially aligned openings in the upper portions of the supporting blocks, and have threaded ends that project from those blocks. The diameter of the block openings is materially greater than that of the pins, and an outer metal ring 83 is mounted rigidly in each opening. Bonded to the inner surface of this ring is a considerably thicker ring of rubber 84, or similar material having the elastic characteristics of rubber. All such material will be referred to herein as rubber-like material. Bonded to the inner surface of this intermediate ring or bushing is an inner metal ring 85 that fits snugly around the adjoining end of the pin. Extending from the inner rings to the weight between them are a pair of sleeves 87 which encircle the pin. In order to fasten all of these members rigidly to the pin so that the swinging

weight will turn the pin and the pin will turn the inner rings, collars 88 are mounted on opposite ends of the pin and are pressed tightly against the outer ends of the adjoining inner rings by means of nuts 89 screwed on the projecting ends of the pin. The result is that when rotation of the head 75 causes the flyweights to swing outward, they turn the pins which thereupon rotate the inner rings in the blocks and stretch the rubber bushings circumferentially.

An important feature of this governor is that the inner rings 86 on the pivot pins do not rub against any supporting elements. Instead, their rotation is absorbed by torsional elastic deformation of the rubber-like bushings that connect them to the outer rings 83. There is no friction or wear between relatively rotating parts, no bearing surfaces that require lubrication, and no starting friction to be overcome. Consequently, the device is exceptionally sensitive to speed changes of the prime mover. Some of the centrifugal force on the weights as head 75 rotates is absorbed by a coil spring 91 connecting the two weights. The distance that the weights can move outward is limited by the outer ends of brackets 92, and the distance they can move inward is adjustably limited by set screws 93 mounted in the inner ends of the brackets. These brackets are secured to the head between blocks 79. The upper ends of the weights which project toward each other are clamped by set screws 94 to the lower ends of resilient metal strips 96, the upper ends of which are clamped by set screws 97 to the rotary member 67 mounted on the lower end of the movable valve member 65 of the governor pilot valve. It will be seen that the rotary member and valve member are rotated and moved up and down by the strips 96 connected to the flyweights.

In order to vary the speed at which the governor must be rotated so as to swing the flyweights out any given distance, the upper end of the pilot valve member 65 above piston 66 is rotatably mounted in a bearing 100 pivotally supported by a bell crank 101. The crank is pivotally supported in a bracket 102 connected to the pilot valve housing 53, and the free end of the crank bears against a disc 103 which is pressed against it by a coil spring 104 carried by the inner end of a non-rotatable threaded rod 105. The outer end of the rod is threaded in a hand wheel 107 rotatably mounted in a projection 108 of case 42. By turning this wheel, the amount of pressure that the spring exerts against the bell crank can be varied. For example, when the pressure is increased, the increased resistance of the pilot valve member to being pulled down requires the governor to rotate at a higher speed in order to swing the flyweights out as far as before. This means that the turbine can reach a higher speed before steam valve 1 will start to close. Consequently, the hand wheel serves as a manually adjustable speed changer for the turbine. It also will be seen that piston 66 operates against the downward pull of the outwardly swinging flyweights on the pilot valve member 65.

When the main shut-off valve is closed and the turbine is idle, the governor flyweights are pulled in against the set screws 93 by means of coil spring 91. This causes the flexible metal strips 96 to raise pilot valve member 65 to its upper position shown in Fig. 3, in which discharge ports 59 are connected with the exhaust port 62. Consequently, spring 47 in governor servo-motor

48 is able to move piston 46 up as far as it will go in the cylinder, thereby rocking arm 39 in a counterclockwise direction. This tilting of the arm will push the right-hand end of lever 36 down and thereby connect inlet 23 of pilot valve 16 with lower passage 21 leading to the bottom of servo-motor cylinder 10. Oil pressure in cylinder 10 will move piston 12 upward and thereby open steam valve 1 wide. Upward movement of this piston will simultaneously lift the left-hand end of lever 36 and thereby restore pilot valve member 30 to centered position.

With the parts of this governing mechanism in the positions described in the preceding paragraph, the main shut-off valve in the steam line is opened so that steam will be delivered through valve 1 to the turbine. As the turbine gathers speed, the flyweights of the governor rotated by it will swing outward and pull valve member 65 downward until the governor pilot valve discharge ports 59 are connected with inlet ports 57 and 53. Oil under pressure then will flow through the valve and pipe 51 to the upper end of servo-motor cylinder 44. The pressure above piston 46 will move the piston downward until the oil pressure in cylinder 56 of the governor pilot valve becomes great enough to move its piston 66 upward against the resistance of the centrifugal force of the flyweights. Closing of discharge ports 59 will trap oil in the upper part of cylinder 44. Fig. 1 of the drawings shows the different parts of the governing mechanism while the turbine is operating at a predetermined speed, depending on the setting of the hand wheel 107. When piston 46 was moved downward in cylinder 44 as shown, it rocked arm 39 in a clockwise direction and thereby raised the right-hand end of lever 36 which, in turn, lifted pilot valve member 30 to admit oil pressure to the upper end of servo-motor cylinder 10. This pressure moved piston 12 down in the cylinder to the position shown and simultaneously pulled down the left-hand end of lever 36 so that valve member 30 was returned to centered position. Downward movement of piston 12 also pulled valve member 2 in the steam admission valve 1 down to the position shown to reduce the delivery of steam to the turbine so that the turbine would operate at the desired speed. Any attempt of the turbine to speed up or slow down will, through the governor, move valve member 65 in the governor pilot valve up or down so as to either admit more oil to governor servo-motor cylinder 44 or release some of the oil therefrom, whereby the steam admission valve will be moved toward open or closed position, depending upon whether the turbine is attempting to go faster or slower. Due to the sensitivity of this speed governing mechanism, variations in speed of the turbine for any given speed setting will be very small.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. In a governing mechanism for a prime mover, a fluid pressure operated servo-motor, a centrifugal device responsive to the speed of the prime mover and including a constantly rotating member that also is movable axially in accordance with said speed, a valve member rigidly

connected at one end to said rotating member coaxially thereof, a piston secured to the opposite end of the valve member, a housing rotatably and slidably receiving the valve member and piston, the housing having a fluid passage therethrough controlled by said valve member and provided with an inlet end for fluid under pressure and a discharge end, a conduit connecting said discharge end with the servo-motor, a spring operatively connected with said piston for opposing the pull of said rotating member on the valve member, and manually operated means for adjusting the force exerted by the spring on the valve member, the housing also having a duct leading from the discharge end of said passage to the adjacent side of the piston to deliver fluid pressure to the piston when the passage is open, whereby to pull the valve member axially to passage-closing position against the pull of said rotating member in the opposite direction. 15

2. In a governing mechanism for a prime mover, a fluid pressure operated servo-motor, a centrifugal device responsive to the speed of the prime mover and including a constantly rotating member that also is movable axially in accordance with said speed, a valve member rigidly connected at one end to said rotating member coaxially thereof, a piston secured to the opposite end of the valve member, a housing rotatably and slidably receiving the valve member and piston, the housing having a fluid passage therethrough controlled by said valve member and provided with an inlet end for fluid under pres- 20 25 30

sure and a discharge end, a conduit connecting said discharge end with the servo-motor, pivoted means connected with said piston, a spring engaging said means to oppose the pull of said rotating member on the valve member, and manually adjustable means for varying the compression of the spring, the housing also having a duct leading from the discharge end of said passage to the adjacent side of the piston to deliver fluid pressure to the piston when the passage is open, whereby to pull the valve member axially to passage-closing position against the pull of said rotating member in the opposite direction.
